Primary Examiner — Catherine R Oliver-Garcia*(74) Attorney, Agent, or Firm* — Ulmer & Berne LLP(57) **CLAIM**

The ornamental design for a rodent trap, as shown and described.

DESCRIPTION

FIG. 1 is a top, front, right side perspective view of a rodent trap showing our new design;

FIG. 2 is a top, front, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a bottom, rear, left side perspective view thereof; and,

FIG. 10 is bottom, rear, right side perspective view thereof. The dashed broken lines in the drawings illustrate the portions of the rodent trap that form no part of the claim.
